METHOD OF MAKING CORNER MEMBERS

Floyd W. Adams, Metuchen, N. J., assignor to The Celotex Corporation, Chicago, Ill., a corporation of Delaware

Application July 13, 1938, Serial No. 218,989

1 Claim. (Cl. 154—2)

In connection with the manufacture and use of products as siding for structures it is contemplated that such products may be manufactured of a base of fibre insulating board or like material so that relatively large units may be employed whereby the number of edge joints may be minimized, there may be provided in connection with such materials thermal insulation achieved through the use of the fibre insulating board as a base material and other advantages, which will become apparent in view of the subsequent disclosure herein, will be derived therefrom.

Siding products in accordance with the disclosure hereof may be briefly described as comprising a base of fibre insulating board or equivalent material, on one face of which, at least, there is applied a coating of adhesive substance which may conveniently be a bituminous substance such as asphalt or the like, or may be a suitable pitch or resin or other adhesive or binder which is relatively weather-resistant and has high adherence. To such adhesive coating when applied to the surface of the base material there is applied a suitable granular substance such as crushed slate, sand, crushed brick or other more or less similar suitable granular material which may be of suitable coarseness. If the granular material is relatively coarse, that is, of about that coarseness of the granular material ordinarily applied to roll roofing, the finished surface will of course be relatively rough and irregular or if the granular material is finely granulated to the order of a dust then the surface provided will be relatively smooth and for example, if a brick dust is used, the finished surface will approximate the appearance and texture of brick.

In connection with the use of products such as has been above generally described, it is necessary in order that a pleasing appearance may be achieved in the application thereof, that there shall be provided corner members which are preformed since it is substantially impossible to obtain a satisfactory corner finish by abutting units at a corner, irrespective of whether such units are merely lapped, or whether an attempt is made to bevel the edges of the units to form a mitered joint at the corner.

It is the particular object of this invention to provide a corner unit for use in connection with a mineral surfaced fibre insulating board or the like designed for wall construction, wherein the such corner piece is prefabricated so as to simu-

late the appearance of a continuous or unbroken corner such as is normally obtained with brick or masonry wall construction. It is a further object of this invention to provide a novel method of manufacturing a continuous, pre-fabricated corner member, such as has been herein disclosed and still further objects and advantages of the invention hereof will become apparent upon consideration of the following description of the invention when taken in connection with the accompanying drawing.

In the drawing:

Figure 1 is a cross-section of portions of two pieces of base material for a corner unit;

15 Figure 2 is a cross-sectional view similar to Figure 1 but showing the application of a strip of material serving to connect the individual pieces together;

20 Figure 3 is another cross-section such as is illustrated in Figure 2, but further illustrating the application of a coating of adhesive to a surface of the material;

25 Figure 4 is a cross-sectional view illustrating a step subsequent to that shown in Figure 3, that is, illustrating a granular material applied to the coating of adhesive substance indicated in Figure 3;

Figure 5 is an enlarged cross-section taken on line 5—5 of Figure 6; and

30 Figure 6 is a perspective view of a portion of a finished corner unit.

In each of the figures of the drawing similar reference numerals will be used to indicate like parts in the various views.

35 In the drawing, in Figure 1 there are illustrated two separate pieces of fibre insulating board or other suitable sheet form base material which separate pieces of the base material are indicated by the numerals 10 and 11. The two pieces of the base material are indicated as lying side by side in a plane and slightly spaced and as having their contiguous edges bevelled rearwardly from faces 12 and 13 toward faces 14 and 15, at an angle, which for each of the separate pieces is illustrated as an angle of 45 degrees, thereby providing contiguous bevelled edges 16 and 17. It is to be understood that if the corner piece is to be used to form a corner piece other than a right angular corner that the bevels 16 and 17 will be at suitable angles with respect to the front faces 12 and 13, so that when such bevels are brought together the desired angularity will be obtained.

40 55 As the first step in the process of forming the desired finished corner pieces the two separate

pieces of the base material, that is, the members indicated by numerals 10 and 11 will be brought together so that the apices of the bevelled portions are brought substantially into contact and there is then applied over the said line of contact and extending substantially over faces 12 and 13, a thin piece of cloth or felt or tough paper or the like, hereinafter referred to as fabric, which is securely adhered to the surfaces 12 and 13 by a suitable adhesive or binder which for example may be a bituminous material, or a pitch, or any other suitable adhesive or binding substance. In the drawing, Figure 2, the strip of fabric or felt or like material is shown as adhered to the surfaces 12 and 13 to secure the base members 10 and 11 together with the apices of their bevels in substantial contact as has been described and is indicated by the numeral 18.

As the next step in the process the entire upper surface of the assemblage illustrated and described, in connection with the showing of Figure 2, is coated with adhesive or binder substance indicated on the drawing by numeral 19. The coating of adhesive or binder substance 19 applied over the surface of the heretofore described assemblage may conveniently be a bituminous substance, that is, an asphaltic material, or suitable pitch, or synthetic resin or other suitable binder or adhesive substance which is highly resistant to deterioration when subjected to the elements.

The next subsequent step in the process of the preparation of the desired units is illustrated in Figure 4, wherein there is illustrated as applied to and imbedded in the adhesive or binder coating 19 a suitable granular substance, which, as hereinbefore mentioned may be roughly granular or which may approach a dust dependent upon the desired appearance of the finished product, the granular material being indicated in Figure 4 by the numeral 20.

In connection with the above described base material for the formation of the desired corner members, it is to be understood that for the purpose of weather-proofing the entire finished unit that the individual and separate sheets comprising the base members 10 and 11 which are processed, as has been described, may be initially entirely water-proofed or weather-proofed by coating with a relatively thin layer of water-proofing such as a bituminous substance, as asphalt for example, or by coating with a suitable pitch or weather resistant resin or the like. It is of course to be understood that the weather resistant coating just referred to may be applied by dipping the individual units 10 and 11 into the coating material or they may be coated by spraying the said substances upon the surfaces thereof or that any other suitable methods may be utilized for achieving the desired result. In coating the units as described, it may be that it is unnecessary to, or undesirable, that the surface 12 and 13 thereof be coated since there is subsequently to be applied to such surfaces the coating 19 which serves to adhere the granular coating 20 to the face of the unit and it is to of course be understood that in coating the base portions 10 and 11 it will be in some cases unnecessary or undesirable to coat those faces thereof indicated by 12 and 13.

Following the operations in the preparation of the base material as has been above described, the next step in the formation of a corner piece is to bend or fold the two portions 10 and 11

thereof toward one another so as to bring the portions 10 and 11 of the base material to a right angle, one with respect to the other, or to such other angle as is provided for by the bevels 16 and 17 as has been described and to bring the such bevelled portions 16 and 17 into contact one with the other. In bending or folding the processed material illustrated in Figure 4 the strip of fabric or like material 18 serves a hinge member and furthermore due to the fact that this strip extends outwardly on each side from the meeting edges of surfaces 12 and 13 the finished surface shown in Figure 4 is continuous around the exterior corner formed by the described bending or folding of the processed sheet.

The corner when bent or folded to shape as described may have secured interiorly thereof of a reinforcing and securing corner strip, of fabric or other suitable material, such as 21 which will of course be secured in place by a suitable adhesive.

The formed corner piece as illustrated in Figure 6 is shown as having along the upper edge thereof an upwardly extending flange portion 22, which it will of course be understood is preferable provided along the appropriate edges of the individual portions 10 and 11 of the base material prior to the various steps of the process of producing corner members as has been herein specifically illustrated. It will of course be understood that the lower edge of a corner unit will be suitably rabbeted to complement a similar flange 22 of an adjacent corner unit. Also it is to be understood that if desired the side edges of a corner unit as distinguished from the top and bottom edges may be formed with complementary flange and rabbet to form closed joints at the edges when associated with complementary flat sheets of similarly surfaced base material.

In applying the granular material 20 to the surface coating 19 which is applied to the faces of the assembled units 10 and 11, it is to be understood that such granular material may have impressed therein a mortar joint pattern or the like to provide a surface simulating bricks, or masonry, or the like or that the granular material may be so applied to the coating that a simulation of brick or the like is achieved.

From a consideration of the above description it will be readily seen that there has been herein described a process whereby there may be constructed corner members for use in applying relatively thin external coverings on structures which corner members due to the particular method of construction are thoroughly reinforced at the corners and are continuous around the corners whereby the finished corner is sealed and there is no tendency for the joint to be open or irregular as would be the case where surfaced members merely brought to the corner in overlapped abutting relation or in bevelled contact.

It will be further seen that the inventions hereof provide a novel method for obtaining a continuous coating across the entire surface of the described corner member and provides a such surface which does not have a tendency to crack or open at the corner, due to the fact that at such joint the coating in which the granular material is imbedded is reinforced by suitable fabric or the like which serves to prevent cracking at the corner either in the operation of the formation of the corner member or in subsequent use thereof.

The inventions hereof having been described in detail, I claim:

The method of formation of an external struc-

tural corner member wherein the initial steps of preparation are carried out on sheet material arranged flatwise, which material without intervening fabrication is folded to form a corner member and which comprises the successive steps: bringing two separate suitably edge beveled base sheets into co-planar relation and in substantially edge to edge contact to provide a V-shaped recess between the sheets, securing the sheets one to the other in such relation by means of a thin flexible strip adhered over and adjacent the line of edge contact of the sheets,

5 applying an adhesive to the face surfaces to which the flexible strip is adhered and coating such surfaces and strip therewith, providing a continuous surfacing with granular material applied to such adhesive coating and embedded therein, folding the treated sheet to bring the beveled surfaces thereof into contact and applying to the interior of the fold a securing and reinforcing strip securing the sheets in their folded 10 relation.

FLOYD W. ADAMS.
